LEG FOR BED SPRINGS

Ralph Weisman, Detroit, Mich.

Application April 28, 1948, Serial No. 23,731

5 Claims. (Cl. 5—310)

SEARCHED

INDEXED

MAILED

1 The present invention pertains to a novel leg for use in converting a conventional metal bed spring to a bed. The principal object of the invention is to provide an inexpensive leg that is easily attached to the frame of the bed spring and by means of which a bed structure is made without the use of a bed frame. To prepare the modified spring for use as a bed, it is only necessary to lay a mattress on the spring and provide the pillows and linens.

As indicated, one of the objects of the invention is simplicity and cheapness, as well as rigidity. With this object in view, the major parts of the device consist of flat stock stamped into proper shape.

Another object of the invention is to utilize one of the usual cross members of the spring as a part of the bracing structure for the leg. In the accomplishment of these several objects, the leg is comprised of a length of angle stock which is substantially flattened at one end for attachment to the frame of the bed spring. The attachment is made, however, through the medium of a U-shaped clip which is first fastened to the flattened end of the leg member and then fastened to the inner surface of the bed spring frame. This form of mounting permits the leg to be fastened at an end of the aforementioned cross member which becomes a part of the bracing structure. A brace, also of flattened stock, has its ends secured respectively to the leg member and to a suitable point on the cross member.

The remaining or lower end of the leg member is preferably fitted with a cap formed with an outward and rounded dent in order not to damage the floor or floor covering.

The invention is fully disclosed by way of example in the following description and in the accompanying drawings in which:

Figure 1 is a side elevation of a bed spring fitted with two legs;

Figure 2 is a perspective view of such a spring, taken from the underside of the spring;

Figure 3 is a side elevation of the leg;

Figure 4 is a section on the line 4—4 of Figure 1;

Figure 5 is a section on the line 5—5 of Figure 3, and

Figure 6 is a section on the line 6—6 of Figure 3.

Reference to these views will now be made by use of like characters which are employed to designate corresponding parts throughout.

In Figure 1 is shown the hollow metal frame 1 of a bed spring across which are laid a suitable

2 number of cross members 2 consisting preferably of flat steel stock. The coil springs 3 are mounted upon the members 2 as well as on additional transverse members 4 and are tied together in a manner well known in the art and not involved in this invention. It will be seen that the members 2 stand for the most part in vertical planes and are twisted at 5 and bent at 6 in order that their ends may be fastened flat against the inner surface of the frame member 1.

This conventional bed spring is converted to a bed by the attachment of four legs constituting the subject matter of this invention. Inasmuch as all the legs are alike, only one of them will be described in detail. Each leg includes a length of angle iron 7 which is substantially flattened at its upper end at 8 for a purpose that will presently be described. This end is secured to the back of a U-shaped clip 9 by rivets 10. The sides 20 of the clip are formed with outwardly extending ears 11 fastened to the inner surface of the frame 1 by suitable means such as bolts or rivets 12. The clip 9 is mounted over the anchored end of one of the cross members 2, adjacent to the bend 6 thereof. The clip 9 is of sufficient depth, when mounted, to receive the end of the cross member 2 as well as the upper end of the leg 7.

On the lower end of the leg 7 is mounted a cap 13 having a pair of ears 14 fastened to the outer surfaces of the angle iron by rivets 15. The base of the cap is stamped out in the form of a button 16 which is rounded for proper engagement with the floor. The cap thus becomes the foot of the device.

The adjacent cross member 2 is utilized as a part of the bracing structure for the leg. A brace 17 in the form of a piece of flat stock has one end bent at 18 for attachment within the angle iron 7 and the other end fastened to the cross member 2 by a suitable fastening 19.

By the means herein described, a conventional bed spring is converted into a serviceable bed without the use of a bed frame. As previously indicated, it is merely necessary to attach four legs to the spring frame 1 near the corners in the manner described. The bed is completed for use with a mattress, pillows and the usual linens. If desired, a head board may be mounted by suitable brackets designed to be inserted and fastened in the clips 9 at one end of the spring frame.

Although a specific embodiment of the invention has been illustrated and described, it will be understood that various alterations in the details of construction may be made without depart-

ing from the scope of the invention as indicated by the appended claims.

What I claim is:

1. In combination with a bed spring frame and a cross member secured to two opposite inner sides thereof, a leg structure comprising a U-shaped clip fastened to one of said sides and over an end of said member, and a leg member having one end received in said clip and fastened to the back thereof.

2. In combination with a bed spring frame and a cross member secured to two opposite inner sides thereof, a leg structure comprising a U-shaped clip fastened to one of said sides and over an end of said member, and a length of angle stock having one end substantially flattened and secured to the inner surface of the back of said clip.

3. In combination with a bed spring frame and a cross member secured to two opposite inner sides thereof, a leg structure comprising a U-shaped clip fastened to one of said sides and over an end of said member, and a leg member having one end received in said clip and fastened to the back thereof, and a rigid brace extending from said leg member to said cross member and secured to an intermediate point of the latter.

4. In combination with a bed spring frame and a cross member secured to two opposite inner sides thereof, a leg structure comprising a U-shaped

clip fastened to one of said sides and over an end of said member, and a length of angle stock having one end substantially flattened and secured to the inner surface of the back of said clip, and a rigid brace extending from said angle stock to said cross member and secured to an intermediate point of the latter.

5. In combination with a bed spring frame and a cross member secured to two opposite inner sides thereof, a leg structure comprising a U-shaped clip fastened to one of said sides and over an end of said member, and a length of angle stock having one end substantially flattened and secured to the inner surface of the back of said clip, and a cap on the other end of said angle stock and having an outward rounded dent to constitute a foot.

RALPH WEISMAN.
